(54) **PLANING MACHINE**

(76) Inventor: **Reid R. Throckmorton**

Reid R Throckmorton City State N.Y.
Setters Patent

The Schedule referred to in this Setters Patent and part of the
same containing a description in the name of the said Reid R
Throckmorton formerly of his improvement in the machine for planing
Boards and other materials -

It all to whom these presents shall come. Be it
known that I Reid R Throckmorton of the City and state of New
York have invented a new and useful improvement in the mode of
planing boards and plank and other materials by machinery
and that the following is a full and exact description thereof.

In the first place the improvement consists
of a frame of wood or iron of about fourteen feet in length and about
four feet in breadth standing on six legs about three feet high, said
frame to have about four or six cross pieces or girders and timber sufficient
to brace to make it firm and strong.

2nd A prop. the frame are placed, two or three well
made of about six inches diameter of hard wood, with turned ends
thinner more beneath said the same above the plane. The middle rollers
bearing pulleys of about sixteen inches diameter, each which attached
to the one end are revolved by means of leather intermediate strap which
passes over a small pulley about six inches diameter, resting upon a vertical
shaft made beneath the frame. The upper rollers are held down by weights
and bars and the weight of which will be in sufficient to get it
so to assist of sufficient thickness of board or plank said frame has
in the centre immediately beneath the plane a red plate of
iron or steel to support the plank during the operation of the plane.

In the feed shaft there is a drum or Ratchet wheel with its
motor of a drum of about fifteen inches diameter of a ratchet
wheel about six feet diameter, the drum to receive a belt from the

and upon a arm of about thirty inches diameter placed beneath the frame and on the shaft on which said arm is placed there is a pulley of about twelve inches diameter. The arm to the ratchet wheel can be attached to the crank shaft or to the plane itself which ever may may be most convenient to give the forward and back ~~hand motion~~

^{the place of}
The implement in this machine consists in placing upon the bed plate or floor of the frame four small pillars or posts upon which are placed two guides or a parallel motion upon these slides or parallel motion is fixed a crop head with Gild or Boules to slide on the guides, so as to cause the crop head to move in a straight line.

The plane is attached to this crop head by means of a strap or permitted party to resolve if desired the strap in said crop head to be attached thereto behind the cutter or knive of the plane and is then extended out in length sufficient to reach a crank which is fixed on an axle in one end of the machine. So a strap, pin - man or shackle bar as it is variously denominative serves as a handle to the plane. The part of the plane on which the knives or cutters are fixed is circular as made so as the circle of the crank will allow the handle connecting the plane to the crank may be straight or otherwise as convenient may regime. The plane should be made of sufficient length to reach about six cutters or knives. The crank should be about six inches which will move the plane in a rectitudinal course twelve inches at each revolution of said crank and at the same time by the rise and fall of the plane handle give a circular motion to the cutters during the reciprocating motion of the plane. That is to say the forward motion of the crank urging the plane ahead, the knives being in a position of a each rise out of the soil each as their individual cut is finished and so on until all of the knives have performed their separate parts and at which time they are all raised off the soil and carried back by said crank and by the next full revolution of said crank said plane returned to cut and

at or otherwise, without the aid of any thing else except the simple
plane handle and the body of the plane being attached to the Crank
shaft will permit it partly to revolve in it.

The Sine Cutters for tongueing and
grooving may be arranged upon similar principles as the aforesaid
wooden plane except that the Crank shaft should be perpendicular
instead of horizontal. The Motion may be given by Rack and Pin
ion, by Pin and planet wheel, by levers and in various other
ways, but the Crank is the simplest and best. What the man
named Clains in the above wooden machine is simply the special
arrangement of the plane & Sine Cutters moved by this or similar
will Crank and resulting in a Compound Motion, reciprocating, re-
tarded, and in part Circular in its operation by connecting the
end of the plane by means of its handle to a Crank or any other
similar Motion.

In testimony whereof I have hereunto subscribed
my name A. J. 1835
